Inventor:
Alois Wunner

UNITED STATES PATENT OFFICE

ALOIS WUNNER, OF NUERMBERG, GERMANY

TELEPHONIC LOUD-SPEAKER

Application filed October 26, 1929, Serial No. 402,753, and in Germany November 1, 1928.

This invention relates to a telephonic loud speaker of the kind wherein the vibratory armature of a magnet system is connected by means of a needle to an acoustic diaphragm. Usually the diaphragm is connected at a single point to the needle. The latter therefore vibrates at right angles to the diaphragm, and it is necessary to support the latter more or less rigidly at the outer edges, an arrangement which leads to a distortion of the sound. The object of the present invention is to produce an arrangement allowing the diaphragm full freedom of movement, and the invention consists in arranging the diaphragm parallel to the needle connecting it to the latter throughout the length thereof.

Fig. 1 of the accompanying drawings represents a sectional view of one form of the improved loud speaker,

Fig. 2 is a front view of the same,

Fig. 3 is a sectional view of a modified form,

Fig. 4 is a front view of the latter, and

Fig. 5 is a side view of a still further form.

The loud speaker comprises the usual magnet system 1 which receives current through leads 7 and which is provided with an adjusting screw 8. The vibratory armature strip 2 of the magnet system is supported at both ends and carries, at substantially right angles, a needle 3 which is connected throughout its length to an acoustic diaphragm 4 so as to hold the latter parallel to its own plane, i. e., substantially at right angles to the armature 2. The diaphragm, which is preferably rectangular in shape, is formed with a channel 5 for the reception of the needle the surface of which is preferably screw threaded or otherwise roughened so as to form engaging points all along the needle.

In the arrangement shown in Figs. 1 and 2, there is only one needle and this is placed in a central position on the armature 2. The diaphragm is extended beyond the needle, and the projecting portion is coiled so as to form a cylindrical or conical sound magnifier 6. When the armature 2 is vibrated under the influence of the magnetic impulses, the vibrations will be transmitted to the diaphragm 4

principally in the direction of the arrows A. The diaphragm will also be oscillated in the directions B about its connecting point with the armature 2. The air column within the cylinder or cone 6 will be set in corresponding vibrations, and a considerable sound volume, faithfully reproducing the original sound, will be obtained from the arrangement.

The sound magnifier 6 may be of oval or annular cross-section instead of round, and it may be provided with apertures, reinforcements, coatings or insertions with a view to modifying the sound and regulating the volume. The diaphragm itself may be treated in a similar manner and it may be bent in different directions if required. Naturally a perfectly straight and continuous diaphragm may also be used.

The entire device may be modified, for instance as shown in Figs. 3 and 4, where two or more needles are provided to which the two limbs of U-shaped diaphragm are connected.

A further modification is shown in Fig. 5 wherein a U-shaped diaphragm is connected to the needles of two separate magnet systems.

The diaphragm may be made of any suitable material such as paper, cardboard, wood, metal, glass or the like, and the rigidity may be varied according to requirements. Tension may be applied to the diaphragm in one or more places if necessary. The length of the needles relative to the diaphragm may be varied.

The device, which can also be used in connection with condenser telephones, is preferably mounted by means of feet on a resonant base.

Being of simpler construction than the usual loud speakers, the loud speaker according to the present invention will also be considerably cheaper.

I claim:

1. A telephonic loud speaker comprising a magnet system fitted with a vibratory armature, a needle carried by said armature, and an acoustic diaphragm connected to said needle throughout the length of the latter.

2. A telephonic loud speaker comprising a magnet system having a vibratory armature, a needle carried by said armature and maintained substantially at right angles thereto, and an acoustic diaphragm arranged parallel to the needle and connected thereto throughout the length of the needle.
3. A telephonic loud speaker as claimed in claim 2 wherein the diaphragm is formed with a channel for the reception of the needle.
4. A telephonic loud speaker as claimed in claim 2 wherein the needle is formed with an uneven surface for engagement with the diaphragm.
5. A telephonic loud speaker comprising a magnet system having a vibratory armature, a pair of needles carried by said armature and arranged substantially at right angles thereto, and an acoustic diaphragm having channels for the reception of said needles.
6. A telephonic loud speaker as claimed in claim 5 wherein the diaphragm is U-shaped and has its limbs connected to different needles.
7. A telephonic loud speaker comprising a pair of magnet systems having vibratory armatures, a needle carried by each armature at substantially right angles thereto, and a U-shaped acoustic diaphragm having each limb connected to the needle of a different magnet system and throughout the length of the needle.

ALOIS WUNNER.
